(57) **CLAIM**

The ornamental design for a split ring, as shown and described.

DESCRIPTION

FIG. 1 is an isometric view of the split ring showing our new design;

FIG. 2 is a first side view thereof;

FIG. 3 is a second side view thereof;

FIG. 4 is a top view thereof;

FIG. 5 is a bottom view and thereof;

FIG. 6 is a first end view thereof; and,

FIG. 7 is a second end view thereof.

The broken lines in the drawings depict portions of the split ring that form no part of the claimed design.

1 Claim, 7 Drawing Sheets
